WREATH KNITTING MACHINE

Frederick R. Slavek, New York, N. Y.

Application November 30, 1945, Serial No. 631,989

5 Claims. (Cl. 66—1)

1

This invention relates to a machine for knitting wreaths, particularly such as are used as a base for floral or other decorative purposes.

An object of this invention is to produce a wreath having a ring base of cardboard, metal, plastic or other substance, covered with cellophane or any flexible material knitted thereon.

Another object of this machine is to produce an ornamental wreath having a pleasing design.

A further object is to produce a mechanically knitted covering of yielding material upon a rigid or semi-rigid ring base.

A final object of this invention is to produce a decorative wreath which will not deteriorate under outdoor conditions.

The invention consists of the construction, combination and arrangement of parts, as herein described, illustrated and claimed.

In the accompanying drawings, forming part hereof, is illustrated one form of embodiment of the invention, in which drawings similar reference characters designate corresponding parts, and in which:

Figure 1 is a side elevation of the complete machine with certain parts indicated by dotted lines to show their direction of travel.

Figure 2 is a plan view of the entire machine.

Figure 3 is an end view taken from the needle end of the machine.

Figure 4 is an elevation in perspective with supporting members and table removed showing the various cams, gears and levers which impart the movements to the machine members.

Figure 5 is a detail view of the latch type knitting needle showing the first knitting motion.

Figure 6 is a detail view of the latch type knitting needle showing the second knitting motion.

Figure 7 is a detail view of the third knitting motion.

Figure 8 is a detail view showing the final knitting motion of the latch type needle.

Figure 9 is a view showing the detail of the knitted wreath.

The various mechanical parts of this machine co-operate to horizontally and reciprocably move a knitting needle of the latch type enabling it to pick up a strand of the weaving material upon each forward stroke. Provision is made to alternately reverse the position of said needle through an arc of 180° in such manner that it picks up a loop first in the up position and then in the down position. The weaving material is moved by its guide so that it is in position to be engaged by the horizontally reciprocating needle. The final major motion imparted by the component parts

2

of this machine is a rotation given the frame upon which the knitting is done, so that each stitch is aligned in close proximity to the next.

Referring to the drawings, and particularly to Figure 1, 10 indicates four legs supporting a plate 11 upon which are mounted two beams 12. Said beams 12 are bored at 13 to accommodate a main shaft 14.

A drive pulley 15 is attached to one end of the shaft 14 and furnishes power to the entire machine. This is accomplished by means of a sprocket wheel 16 and drive chain 17 located next to the drive pulley 15 on the main shaft 14. An adjustable crank 18 located on the opposite end 19 of the main shaft 14 also serves to transmit motion, imparted to it by the drive pulley 15, to the machine.

An eccentric cam 19 is rigidly attached to the middle of the main shaft 14. This cam 19 revolves within a bearing 20 to which a drive rod 21 is threaded, imparting a reciprocating motion thereto.

The reciprocating movement of the drive rod 21 is transmitted through a clevis 22, integral therewith, to an arm 23 pivoted at one end on a shaft 24 held in a bearing 25 attached to the plate 11. The other end of the arm 23 terminates in a fork 26 which engages a groove 27 machined in the end of the needle guide shaft 28. The aforementioned reciprocating motion is thereby carried to the needle.

The guide shaft 28 passes through a bearing 29 bored in a bracket 30 mounted upon a table 31 supported by the beams 12 and 32. The end of the said guide shaft 28 is provided with a clamp 33 for holding the latch type knitting needle 34.

The previously described rotary motion imparted to the needle 34 by means of which it alternately picks up loops of the material in an up and down position, stems from the sprocket wheel 16 located on the main shaft 14. The sprocket wheel 16 is linked to a driven sprocket wheel 35 by the drive chain 17. Said driven sprocket wheel 35 is mounted upon the end of a driven shaft 36 supported by the two beams 32. It is necessary to effect a reduction of speed from the main shaft 14 to the driven shaft 36 to coordinate the movements of the machine. This is done by the well known speed reduction method.

Referring to Figure 4, 37 is an eccentric cam attached to the driven shaft 36. A gear rack 38, cut in the end of a vertical arm 39 is raised and lowered by a horizontal arm 40, integral therewith, which rides upon the eccentric cam 37.

By referring again to Figure 1 it can be seen

that the gear rack 38 is meshed with a gear 41. Said gear 41 is slidably keyed to the guide shaft 28. A spline 42 in the guide shaft 28 enables it to reciprocate horizontally without becoming detached from the keyed gear 41.

It is necessary, for the operation of this machine, that the material 43 to be knitted be engaged upon the reciprocating needle. A vertical and lateral movement of the material 43 is necessary to accomplish this. An eyelet 44, through which the material 43 is passed, is provided for this purpose.

The desired vertical motion of the said eyelet 44 is accomplished by a cam 45, best shown in Figure 4, rotatably held by the driven shaft 36. The rotation of the shaft 36 causes the cam 45 to depress a lever 46. The lever 46 is pivoted at one end upon a shaft 47 held in a pedestal bearing 48 attached to the plate 11. The opposite end of the lever 46 is connected to a link 49 which joins the lever 46 to an arm 50. A spring 51 secured to the underside of the table 31 engages a small shaft 52 to return the lever 46 to its original position following each depression by the cam 45.

The arm 50 is fastened by a pin to a slidable shaft 53, supported by two beams 32, which transmits the torque imparted to it by the above described mechanism, to a rocker arm 54 mounted upon it. The rocker arm 54 is furnished with a longitudinal slot 55 at its outer end to enable it to lift the eyelet shaft 56 vertically.

The lateral motion of the eyelet 44, necessary in the knitting operation, is the result of the action of a third cam 57 attached to the driven shaft 36. This is best shown by referring to Figure 3. Said cam 57 alternately raises and drops a curved arm 58 which rests upon the inner face of a flanged collar 59 held to the sliding shaft 53 by a pin. When the arm 58 is raised it forces the sliding shaft 53 to the right, causing the rocker arm 54 engaging the eyelet shaft 56 to move with it.

A small spring 60 is slipped over the portion of the sliding shaft 53 which projects beyond the left hand vertical beam 32. It is compressed between the beam 32 and a small collar 61 secured to the end of the sliding shaft 53. The function of this spring 60 is to return the sliding shaft 53 to its original position when the pressure of the curved arm 58 is released.

The remaining operation performed by this invention is the rotation of the frame 62 upon which the knitting is done. Power for this operation is taken from the crank 18 attached to the end of the main shaft 14, shown in perspective in Figure 4. A pawl 63 attached to said crank 18 engages a ratchet gear 64. In this manner a shaft 65, to which the ratchet gear 64 is keyed, is driven. Said shaft 65 rotatably supports two worms 66 and is held by four pedestal bearings 67 secured to the plate 11.

By referring to Figure 3 it may be seen that the motion of the shaft 65 imparted by the pawl 63 and ratchet 64 is transmitted by means of the worms 66 (not shown) to two worm wheels 68. The worm wheels are securely attached to two individual vertical shafts 69 which pivot upon bearings 70 set in the plate 11. The vertical shafts 69 pass through two bearings 71 mounted in the table 31 and terminate in worms 72.

A bracket 73 mounting three spools 74 is attached to the table 31. Said spools 74 are grooved 75 along their periphery to receive the frame 62 upon which the knitting is to be done and the two lower spools are provided with worm wheels

76 to engage the worms 72 on the vertical shafts 69. The frame 62 is thereby caused to rotate after each knitting stitch.

The operation of the latch type knitting needle 34 can best be understood by reference to Figures 5, 6, 7 and 8.

In Figure 5 the needle 34 has been extended by its guide shaft 28, beyond the frame 62 to pick up a loop of material 43. The eyelet 44 has just placed the loop upon the needle 34 by moving laterally in the slot 77 provided for the travel of the eyelet shaft 56. In this figure the eyelet 44 has just moved down for the next operation.

In Figure 6 the guide shaft 28 has pulled back the needle 34 thereby drawing the loop through the frame and finally through the standing loop as shown in Figure 7.

The dotted lines in Figure 7 indicate the position of the needle 34 following rotation by means of the gear 41 attached to the guide shaft 28. The latch arrangement swings open permitting the hook to slip through the loop and catch the knitting material, as shown in Figure 8, below the frame 62. The knitting cycle is then repeated.

Figure 9 illustrates the knitted wreath resulting from the above described operations. The frame 62, the material to be knitted 43 and the attractive design achieved by this invention may be seen in this view. The hidden side of the wreath presents a series of closely spaced strands disposed side by side, covering the frame 62. The wreath is not claimed herein but is the subject of a divisional application Serial No. 1,217 filed January 8, 1948.

Where a colored cellulose strip is used as the knitting material, a constricting eye shown in Figure 1 is employed immediately preceding the moving eyelet 44. In this manner a thin flat strip of material is crushed into a strand 43 for easy knitting.

Having thus fully described the invention, what is claimed as new and desired to be secured by Letters Patent of the United States, is:

1. In a machine for knitting wreaths upon a frame, means to support and rotate said frame comprising, in combination, a drive shaft, a crank connected thereto, a pawl actuated by said crank, a ratchet gear rotated by the pawl, a shaft carrying said ratchet, a series of worm gears secured to the ratchet shaft and spools attached thereto and engageable with said frame, means to vertically and laterally move the material to be knitted and a horizontally reciprocating needle engaging said material.

2. In a machine for knitting wreaths upon a frame, means to support and rotate said frame, means to vertically and laterally move the material to be knitted comprising, in combination, a rockable and laterally slidable shaft, a driven shaft mounting two cams, arms actuated by said cams to rock and shift said slidable shaft, an eyelet shaft coupled to the slidable shaft and vertically and laterally moved thereby and a horizontally reciprocating needle engaging said material.

3. In a machine for knitting wreaths upon a frame, means to support and rotate said frame comprising, in combination, a drive shaft, a crank connected thereto, a pawl actuated by said crank, a ratchet gear rotated by the pawl, a shaft carrying said ratchet, a series of worm gears secured to the ratchet shaft and rods attached thereto and engageable with said frame, means to vertically and laterally move the material to be

knitted comprising, in combination, a rockable and laterally slideable shaft, a driven shaft mounting two cams, arms actuated by said cams to rock and shift said slideable shaft, an eyelet shaft coupled to the slideable shaft and vertically and laterally moved thereby and a horizontally reciprocating needle of the latch type attached to a guide shaft by a clamp, said shaft and needle being rotated through an arc of 180° after each knitting stitch.

4. In a machine for knitting wreaths upon a frame, means to support and rotate said frame, means to vertically and laterally move the material to be knitted and a horizontally reciprocating needle attached to a guide shaft said shaft and needle being rotated through an arc of 180° after each knitting stitch by a mechanism comprising, in combination, a driven shaft, an eccentric cam mounted upon said driven shaft, a vertical shaft, a gear rack cut into one end of said vertical shaft, an arm integral with the vertical shaft which rides upon the eccentric cam, a gear meshed with the gear rack and keyed to the said guide shaft, and a clamp attached to the guide shaft holding said needle.

5. In a machine for knitting wreaths upon a frame, means to support and rotate said frame,

means to vertically and laterally move the material to be knitted and a horizontally reciprocating needle of the latch type attached to a guide shaft said shaft and needle being rotated through an arc of 180° after each knitting stitch by a mechanism comprising, in combination, a driven shaft, an eccentric cam mounted upon said driven shaft, a vertical shaft, a gear rack cut into one end of said vertical shaft, an arm integral with the vertical shaft which rides upon the eccentric cam, a gear meshed with the gear rack and keyed to the said guide shaft, and a clamp attached to the guide shaft holding said needle.

FREDERICK R. SLAVEK.
